UNITED STATES PATENT OFFICE.

JAMES L. CRANE, OF CLEVELAND, OHIO.

SHOW-CASE OR SHOW-FRONT.

SPECIFICATION forming part of Letters Patent No. 739,295, dated September 22, 1903.

Application filed August 26, 1898. Serial No. 689,546. (No model.)

To all whom it may concern:

Be it known that I, JAMES L. CRANE, residing at Cleveland, county of Cuyahoga, and State of Ohio, have invented certain new and useful Improvements in Show-Cases or Show-Fronts; and I do hereby declare the following to be a full, clear, and exact description of the invention, such as will enable others skilled in the art to which it pertains to make and use the same.

My invention relates to improvements in show-cases and show-fronts, and more especially to a corner-clamp instrumental in securing together upright glass plates of a show-case or show-front that are arranged at an angle to and about each other, and my invention pertains also to a top corner-clamp for use in the construction of show-cases and having not only means instrumental in preventing endwise displacement of the connected upright glass plates, but also improved means instrumental in holding the top plate of the show-case downwardly upon the said upright plates.

In the accompanying drawings, Figure I is a top plan of a corner of a show-case embodying my invention. Fig. II is a vertical section on line II II, Fig. I. Fig. III is a horizontal section on line III III, Fig. II. Fig. IV is a top plan of the corner of a show-case involving a modification that is within the scope of my invention. Fig. V is a vertical section on either one of lines V V, Fig. IV.

Referring to the drawings, *a* and *b* designate the upper portions of two upright glass plates or sides of a show-case or show-front, which plates are arranged at right angles to each other in the case illustrated, and *d* designates the top plate of the said show-case, which top plate rests upon the aforesaid upright plates *a* and *b*.

My improved corner-clamp comprises an external jaw *e* and an internal jaw *g*. The external jaw *e* is an angle-piece embracing the external corner formed at the upper ends of the upright glass plates below the top plate, and consequently has two arms or wings *e'* *e''*, overlapping and arranged to bear against the outer side of plates *a* and *b*, respectively. The internal jaw *g* is an angle-piece fitting against the internal sides of the upright plates *a* and *b* opposite to the external jaw and com-

prises, therefore, two arms or wings *g'* *g''*, arranged to bear against the inner side of plates *a* and *b*, respectively, opposite the arms or wings *e'* and *e''*, respectively, of the external jaw. The corner-clamp is provided with an external screw *h*, arranged in a horizontal plane and extending through the hole *g*³, formed centrally of the internal jaw and through the corner formed between plates *a* and *b* into the external jaw. The screw *h* engages a correspondingly arranged and threaded hole *e*³, formed in the corner of the external jaw. The plates *a* and *b* are recessed 55 in their contiguous or adjacent ends, as at *c*, to accommodate the location and operation of the said screw, that at its inner end is provided with a countersunk head *h'*, that is arranged to bear or crowd the internal jaw against the internal surfaces of the plates *a* and *b*. The screw-receiving hole *g*³ in the internal jaw is countersunk, as required, to accommodate the reception of the counter sunk head of the screw, and the said head is provided 60 with a recess *h*² for accommodating the application of a screw-driver. The external jaw, it will be observed, serves as a nut for the screw, and it is obvious that the two jaws are actuated toward each other, so as to clamp 65 the plates *a* and *b* between them upon turning the screw in the one direction and are loosened relative to the plates upon turning the screw in the opposite direction. One of the jaws, and preferably the external jaw, is 70 provided with two lugs *e*⁴ and *e*⁵, that engage niches *a'* and *b'*, respectively, formed in the plates *a* and *b*, respectively, and the said engaging lugs and niches prevent endwise displacement of the said plates. The lugs *e*⁴ and *e*⁵ 75 are formed upon the different arms or wings *e'* and *e''*, respectively, of the external jaw, and in Fig. I are formed upon the inner side of the said jaw and in the same horizontal plane with the screw-receiving hole *e*³ of the 80 jaw, and the engaging niches *a'* and *b'* are formed in the external sides of the plates *a* and *b* and in the same horizontal plane with the recesses *c*, that are formed in the adjacent ends of the said plates for the accommodation, 85 as already indicated, of the location and operation of the screw *h*. The location of the lugs *e*⁴ and *e*⁵ and the screw *h* in the same horizontal plane facilitates the formation of 90

the recesses formed in the glass plates and saves labor and expense in the assemblage of the parts. In Figs. IV and V the lugs e^4 and e^5 are formed upon the upper ends of the 5 arms or wings of the external jaw and project inwardly in a horizontal plane and engage recesses a^2 and b^2 , formed in the upper ends of the plates a and b , respectively. The internal jaw at its upper end and inner side 10 is provided with a web g^4 , that forms a bearing for the top plate d and connects and braces apart the two arms or wings g' and g^2 of the said jaw, and is provided with a vertical screw-threaded hole g^5 , that is engaged by the correspondingly-threaded shank 15 of the vertically-arranged screw k , that is introduced through a hole d' , formed in the top plate d of the show-case, and has a smooth polished head k' , engaging the upper side of 20 the said plate and arranged to bear the said plate downwardly upon the aforesaid web and downwardly upon the upright plates a and b . The web g^4 forms a nut for the screw that has its shank in the latter's lower end, 25 provided with a recess k^2 for accommodating the application of a screw-driver. It is obvious that upon turning the screw in the one direction the top plate d will be caused to bear downwardly upon the aforesaid web g^4 30 and upright plates a and b , and the top plate will be loosened relative to the said web and upright plates upon turning the screw in the opposite direction. The construction thus described is important, because it accommodates 35 the employment of a screw that has a smooth unrecessed head, because it does not require recessing or cutting away of the upright plates a and b and because it is not only cheap, but possesses great efficiency and 40 durability.

While ordinarily a show-front has not a glass top and would not require the screw k , yet projecting show-fronts, especially when the latter are located in an arcade below and 45 projecting from an elevated promenade or walk, could have such tops. I would remark, also, that a show-case or show-front may be provided with my improved corner-clamp in all of its corners, top and bottom, and at 50 points intermediate between the bottom and top, if desired or advisable, and if at points thus intermediate may, by means of the web g^4 and screw k , be instrumental in supporting glass shelves. I would remark, furthermore, 55 that the location of the means operatively connecting the two jaws of the corner-clamp together between the two lugs e^4 and e^5 renders practicable not only the use of short lugs and correspondingly-shallow niches in the glass, 60 but the use of a single screw for clamping the glass between the jaws and for retaining the said lugs positively in engagement with the said niches and accommodates and facilitates the separation and assembling of the 65 parts. It will be observed, also, that my improved corner-clamp accommodates the overlapping, by the outer jaw of the clamp, of the

top plate d , so as to prevent the said jaw from marring the appearance of the show-case, and the clamp clamps the top plate tightly against 70 the upper edges of the upright plates without interfering with the projection of the said top plate any distance beyond the outer sides of the upright plates.

What I claim is—

1. In a show-case or show-front, the combination, with two upright glass plates arranged at an angle to each other, and a top plate overlapping the upper edges of the corner formed between the upright plates, of an outer jaw 80 arranged against the outer sides of the upright plates adjacent to and below the top plate, an inner jaw arranged against the inner sides of the upright plates adjacent to and below the top plate, a connection between 85 the said jaws, and a vertically-adjustable screw extending through the top plate and attached to one of the aforesaid jaws and having its upper end provided with a head arranged to hold the top plate down upon the 90 upper edges of the upright plates.

2. In a show-case or show-front, the combination, with two upright glass plates arranged at an angle to each other, and a top plate overlapping the upper edges of the upright plates, 95 of a corner-clamp comprising the following: a jaw having arms or wings arranged to bear against the outer sides of the upright plates, a jaw having arms or wings arranged to bear against the inner sides of the upright plates, 100 an operative connection between the two jaws at the corner or angle of the clamp, and lugs formed upon the inner sides of the arms or wings of one of the said jaws at opposite sides, respectively, of and at the same elevation as 105 the aforesaid operative connection, and means holding the top plate down against the upper edges of the upright plates.

3. In a show-case or show-front, the combination, with two upright glass plates arranged 110 at an angle to each other, and a top plate overlapping the upper edges of the upright plates, of a corner-clamp comprising the following: a jaw having arms or wings arranged to abut against the outer sides of the upright plates; 115 an inner jaw having arms or wings arranged to abut against the inner sides of the upright plates, and provided, at its upper end, with a member extending in under the top plate; a single operative connection between the two 120 jaws at the corner or angle formed by the upright plates, and a vertically-adjustable screw extending through the top plate and attached, below the said top plate, to the jaw member which as aforesaid extends in under 125 the top plate, which screw is provided, at its upper end, with a head arranged to hold the top plate down upon the upright plates.

Signed by me at Cleveland, Ohio, this 24th day of August, 1898.

JAMES L. CRANE.
